Primary Examiner — Barbara Fox*Assistant Examiner* — Dana K Weiland(74) *Attorney, Agent, or Firm* — Foley & Lardner LLP(57) **CLAIM**

We claim the ornamental design for a display for user interface, as shown and described.

DESCRIPTION

FIG. 1 is a top, front, right perspective view of a display for user interface showing the new design; FIG. 2 is a front elevation view thereof; FIG. 3 is a rear elevation view thereof; FIG. 4 is a left elevation view thereof; FIG. 5 is a right elevation view thereof; FIG. 6 is a top plan view thereof; and, FIG. 7 is a bottom plan view thereof.

Broken lines formed by equal length dashes illustrate portions of the display for user interface that form no part of the claimed design. Broken lines formed by unequal length dashes (i.e., dash-dot) illustrate bounds of the claim and form no part of the claimed design.
